YARN SUPPLYING MECHANISM FOR
KNITTING MACHINES

Arthur Shortland, Leicester, England

Application December 31, 1951, Serial No. 264,313
In Great Britain November 20, 1950

17 Claims. (Cl. 66—140)

1

This invention relates to yarn supplying mechanism for knitting machines, and concerns such mechanism of the kind adapted automatically to introduce a yarn to, and effect withdrawal of the same from, the needles at predetermined times.

It is principally the intention to apply the invention to a yarn feeding and changing mechanism capable of being operated selectively at predetermined times for the purpose of substituting a desired one of a plurality of yarns for another of a different character, e. g. colour or/and count, texture or quality, according to requirements.

The invention may accordingly be applied to a horizontal striping mechanism. Moreover, although broadly applicable to a knitting machine of any appropriate type, it is mainly intended to apply the invention to a circular rib knitting machine either of the cylinder and dial or the superimposed needle cylinder type.

The object of the invention is to provide, in a knitting machine, an improved form of yarn supplying mechanism of the kind referred to adapted to operate in a novel manner, as will be hereinafter described.

Broadly considered, the improved mechanism comprises, in combination, a fixed guide through which a yarn from a supply passes when feeding to the needles of the machine, an associated yarn gripper which is movable from one position in which it grips the yarn and holds it in a non-feeding position clear of the needles, to another position in which the yarn, still held by the gripper, is favourably disposed for introduction to the needles, and placer means operable to engage the yarn so disposed and to take it to the needles.

After the yarn has been introduced to the needles by the placer, the gripper, without any further movement thereof bodily is suitably actuated to release the yarn. When, on the other hand, the feeding yarn is next required to be withdrawn from knitting, the gripper is actuated to engage and trap the yarn and hold it in its non-feeding position. Severance of the withdrawn yarn may be effected as a consequence of a shearing action resulting from relative movement between operative parts of the gripper. Alternatively, severance of the withdrawn yarn may be effected solely by the pull of the needles thereon: in this alternative case the withdrawn yarn, when gripped, breaks under tension.

The yarn gripper is therefore distinct from

2

a yarn guide or feeder having a hole or throat through which a yarn passes and which is itself movable from a yarn feeding position to a non-feeding position, and vice versa.

In its preferred form, the improved yarn supplying mechanism is designed to deal with a plurality of yarns e. g. as many as three or four or more, to which end it is furnished with a series of fixed yarn guides, one to each yarn, and a corresponding series of yarn grippers operable selectively for effecting substitution of one yarn for another. In this embodiment the gripper means may consist either of a single yarn placing member common to all of the grippers, or of a plurality of placers—one associated with each gripper. For the sake of convenience, the following further description will be confined to this preferred form of the mechanism, without, however, limitation in this respect.

In the case of a machine of the cylinder and dial type, a yarn placer having a shank or stem with a hooked operative end may be located in one of the needle tricks or grooves of the dial, in which instance means on the customary dial cam plate, or on an associated part, may be provided for projecting the placer radially from, and retracting it into, the dial.

Alternatively, a yarn placer in the form of a hooked or equivalently shaped pivoted member, common to all of the grippers, may be actuated, through any suitable intermediate connections, either from the same means used for controlling the grippers, or from separate means working in timed relation therewith.

In a modification, however, a separate yarn placer may be suitably mounted in association with each gripper and arranged to be reciprocated by any convenient means.

The yarn grippers may extend parallel to each other, or they may converge onto or towards a common point to enable each yarn, when placed in its feeding position, to be introduced to and initially taken by the least possible number of needles.

In the preferred form of the improved yarn supplying and changing mechanism, the means for selecting and controlling the grippers, the means for effecting the relative movements of the operative parts of the grippers, and, in appropriate cases, also the placer means for engaging and introducing to the needles a favourably disposed yarn, are all controlled from cam means mounted upon a common shaft in turn adapted to be turned to an appropriate extent

at desired intervals of time, e. g. at the dictates of a timing or control chain or equivalent.

Specific constructional examples of the invention embodied in horizontal striping mechanism applied to a circular knitting machine of the cylinder and dial type will now be described with reference to the accompanying drawings, wherein,

Figure 1 is a side elevational view of one form of said striping mechanism showing a pivoted gripper holding a yarn in its non-feeding position and illustrating rotary cam means and intermediate connections for selecting and controlling the yarn grippers.

Figure 2 is a similar side view of the mechanism but showing a selected yarn gripper lowered to dispose a yarn favourably for engagement by the placer,

Figure 3 is a plan view corresponding to Figure 2,

Figure 4 is a detail perspective view depicting the fixed yarn guides, the placer and a few of the dial needles in the machine,

Figure 5 is a vertical sectional view of so much of the head of the cylinder and dial machine as is necessary to illustrate the application of the invention thereto, the figure serving to show more particularly the means for actuating the placer, and the controlled means for turning the cam shaft at appropriate times,

Figure 6 is a composite diagrammatic plan view of the said placer actuating and control means with the dial cam plate and the top plate of the machine removed for clarity,

Figures 7-10 are detail side views illustrating successive stages in the operation of the striping mechanism,

Figure 11 is a side view, partly in section, of a further form of the invention, and

Figure 12 is a fragmentary longitudinal sectional view of one of the yarn grippers included in this further example.

Like parts are designated by similar reference characters throughout the drawings.

In the example now to be described with reference to Figures 1-10, a bracket B constituting a combined feeder plate and latch guard is attached, e. g. by means of screws, to the top of the outer edge portion of the stationary dial cam plate 1 of the machine. The actual feeder plate portion 2 of the bracket B extends outwards from the top of the latter, whilst the latch guard, spaced beneath the feeder plate 2, is indicated at 3. The feeder plate 2 is fitted with a series of yarn guides in the form of tubular pot eyes 4. These guides, of which there are four in this example, are thus located above the cylinder and dial needles 5 and 6 respectively on the outside of the needle circle. At a location between the feeder plate 2 and the latch guard 3, the bracket B is provided with a horizontal flange 7 in which are formed slots 8 for the further guidance of a feeding yarn. The latch guard 3 is formed at one end with an outwardly extending radial extension 9 around which a feeding yarn is drawn as and when taken and knitted by the needles. On a horizontal common fulcrum pin 10 fitted in a vertically disposed plate-like bracket 11 fixed in position upon the top plate 12 of the machine is pivotally mounted a series of four yarn grippers G—one to each fixed pot eye 4. Each gripper comprises a tube 13 the inwardly directed operative end of which is longitudinally split at opposite sides as indicated at 14 suchwise as to provide opposed inherently springy portions 15 and, con-

tained within the said tube, a longitudinally slideable rod 16. The inner, i. e. operative, end of this rod is formed with a hook 17 and at its tail end the rod extends outwardly for some distance beyond the corresponding end of the tube 13. To prevent each hooked rod 16 from turning within and relatively to the relevant tube 13, the rod is fitted with an upwardly extending pin 18 arranged for movement in a slot 19 (Figure 3) cut in the upper side of the tube. Each hooked rod 16 is, therefore, slideable within its tube 13 to an extent corresponding to the length of the slot 19. In this regard, whenever the rod is retracted to the position where its pin 18 is located at the rear end of the slot 19, the hooked end of the rod will be accommodated entirely within the tube 13 so that the opposed springy portions 15 exercise a frictional grip thereupon. When, however, the rod is pushed forwards (that is to say, inwardly with respect to the central axis of the machine), the hook 17 will project from the split end of the tube 13 to the extent permitted by engagement of the pin 18 in the front end of the slot 19. At its tail end, each gripper tube 13 is fixed in a tubular carrier component 20 having an upstanding lug or ear 21 drilled with a hole through which the common fulcrum pin 10 extends. At its rear end each lug or ear 21 is provided with an upwardly directed tooth 22 disposed immediately below and in line with a selector disc 23. The four suitably spaced parallel selector discs 23 are centrally bossed and rigidly secured side by side upon a shaft 24 mounted for rotation in a bearing 25 in the bracket 11. The peripheries of the discs 23 have formed therein prearranged notches such as those indicated at 23a in Figures 1 and 2. Now with the tooth 22 of any gripper G engaged with an un-notched portion of the periphery of the corresponding selector disc 23, that gripper will be disposed in its normal raised position shown in full lines in Figure 1: it is in this position that a gripper holds an inactive yarn, such as that indicated at Y, clear of the needles. But assume now the shaft 24 is turned anti-clockwise (as viewed in Figure 1) to the extent of positioning a notch 23a in the disc 23 directly over the tooth 22, then the gripper G, thereby selected, will be permitted to swing down to the full line position of Figure 2 in which position the yarn, still trapped between the rod 16 and the split end of the tube 13, will be favourably disposed for introduction to the needles 5 and 6 by means of a yarn placer 26 hereinafter to be described. Each gripper G is influenced by means of a tension spring S whereby it is swung down whenever the latter is selected by virtue of its tooth 22 entering a notch 23a in the corresponding selector disc 23.

The assemblage of selector discs 23 for selectively controlling the grippers G has associated therewith a toothed wheel 27 which is rigidly secured upon the inner end of the shaft 24, and the notches 27a in this wheel are adapted to be engaged seriatim by a profiled rib 28a on a cylinder cam 28 secured upon a vertical cam shaft 29. As shown in Figures 1, 2 and 5, the cam shaft 29 is mounted to turn in bearings on and in the bracket 11 and the top plate 12 respectively and, at desired intervals, dictated by a timing chain 30 (Figures 5 and 6), this shaft is turned through a complete revolution at which times the complete assemblage of selector discs 23 will be racked round one step.

Both for controlling the downward swinging movement of any selected gripper G under the action of its spring S, and also for subsequently

raising the gripper to a position in which it can engage and trap a yarn to be withdrawn from knitting, there is provided at the inner side of the series of grippers a pivoted element 31 fitted with a comparatively long pin 32 which extends transversely beneath the gripper tubes 13. The tail end of the element 31 is fulcrummed at 33 upon the lower extremity of a downwardly extending lever 34 which latter at its upper end is rigidly secured to the inner end of a short spindle 35 mounted to turn in a bearing in the bracket 11. The spindle 35 projects right through the bracket and has secured upon its outer end a short arm 36 furnished at 37 (Figures 1 and 2) with a pin or a roller engaged in an appropriately contoured track 38 formed in a grooved cylinder cam 39 secured upon the vertical cam shaft 29. The pivoted element 31 is at all times maintained more or less upright, although, for a reason hereinafter to be explained it is permitted a certain amount of pivotal movement back and forth in relation to the lever 34. Such movement of the element 31 is controlled by contact of a pin 40 on the element with an inwardly curved cam surface 11a defining the lower side of a recess in the bracket 11. The extent of the said movement in both directions is limited by two spaced pins 41 and 42 fixed in the lower extremity of the lever 34 and arranged for contact with respectively opposite edges of the pivoted element. The construction and arrangement of the mechanism so far described are such that immediately prior to each rack of the assemblage of selector discs 23 to effect selection of a gripper G, the lever 34, carrying the element 31, is initially swung upwardly to a small extent sufficient to enable the pin 32 to lift all of the grippers into the chain line position indicated in Figure 1 with the object of temporarily lowering the teeth 22 clear of the peripheries of the selector discs, thereby enabling the complete assemblage of the latter to be freely turned to the extent of one step. Thereupon, the lever 34 is lowered into the full line position shown in Figure 2 so that the downward swing of a selected gripper under the action of its spring S will be controlled by virtue of the tube 13 of that gripper resting upon the downwardly moving pin 32. The selected gripper is then swung up towards its normal rest position as the result of an upward swing of the lever 34 and, of course, a corresponding movement upwardly of the transverse pin 32. The various movements just described take place during one complete revolution of the grooved cylinder cam 39—as will be more fully described hereinafter.

For effecting the required axial movements of the hooked rod 16 within the tube 13 of a selected gripper G in timed relation with the swinging movements of the latter about the fulcrum pin 10, there is provided a bell crank lever 43 a downwardly extending longer arm 43a of which is rigidly secured upon one end of a short spindle 44 mounted to turn in yet another bearing in the bracket 11. The spindle 44 extends right through the bracket and has rigidly secured upon its opposite end a comparatively short arm 43b of the bell crank lever 43 which arm is fitted with a pin or a roller such as 45 engaged in an appropriately contoured upper track 46 formed in the aforesaid grooved cylinder cam 39. At its lower extremity, the downwardly extending longer arm 43a is provided with a lateral extension 47 adapted for action upon the tail end of the hooked rod 16 of an appropriate gripper G for the purpose

of pushing this forwardly and effecting projection of its hook 17 from the relevant tube 13. At a short distance above the lateral extension 47 there is provided on the arm 43a a further laterally extending portion 48 the underside of which is grooved or channelled, as indicated at 49 in Figures 1, 2 and 3, to receive an upstanding pin 50 on the rod 16 of a selected gripper. Thus, as a consequence of turning movements imparted to the bell crank lever 43 by the grooved cylinder cam 39, the hooked rod 16 of a selected gripper will be pushed forward and drawn back at appropriate times by virtue of the grooved or channelled portion 48 acting on the pin 50.

The precise phases in a complete cycle of movements of the appropriate grippers and the yarn placer 26 necessary to effect a change of yarn will be presently described. In the meantime the said placer and the means for actuating the same, and also the controlled means for turning the cam shaft 29 will be described with reference to Figures 5 and 6.

As will be seen more clearly in Figure 5, the placer 26 in this particular example is in the form of a slender shank or stem with a hooked operative end 26a. The placer 26 is located in one of the normal needle tricks cut in the dial 51, and the tail end of the shank or stem, which extends radially inwards beyond the inner edge of said dial, is formed with an upstanding actuating butt 52. This butt is permanently engaged in a forked outer end 53a of a lever 53 which is pivotally mounted at 54 (see Figure 6) upon the top of the centrally bossed dial carrier 55. In Figure 5, the actuating butt of a dial needle is indicated at 56. As depicted in Figure 6, the top side of the forked lever 53 is formed with a triangularly shaped cam portion 57 the relatively splayed cam faces 58 and 59 of which are arranged to be acted upon alternately by pins 60 and 61, respectively, fixed to the underside of the horizontally flanged portion 62 of the hub 63 carrying the stationary dial cam plate 1 of the machine. Accordingly, as the machine revolves, the forked lever 53 will be caused, by contact of the pins 60 and 61 with the cam faces 58 and 59, to make an oscillation as the result of which the hooked operative end of the placer 26 will first be projected outwardly from and then immediately retracted into the dial at the yarn feeding location; this happens whether or not a yarn change is to be made at this location.

The means for rotating the vertical cam shaft 29 at desired times includes a lever 64 which is centrally fulcrummed upon a bracket 65 (see Figure 5) serving to carry an intermittently driven sprocket 66 over which the timing chain 30 is passed. This chain is fitted at predetermined points with lateral studs such as 67 for engagement at required times with the toe 64a of the lever 64. The tail end of this lever is connected with means 68 of any suitable character adapted for action upon an angularly displaceable ring 69 embracing the periphery of the top plate 12, the arrangement being such that whenever, owing to the absence of a stud on the chain, the toe 64a of the lever drops, the ring 69 will be angularly displaced in a clockwise direction—as seen in Figure 6—whereas each time the said toe is lifted the ring will be restored to its original position. Provided on, and projecting inwardly beneath the ring 69 is a bracket 70 beneath which is pivotally mounted a spring-in-

fluenced latch 71. In its normal position shown in Figure 6, the latch 71 engages and holds in its inoperative position a toothed quadrant 72 arranged for co-operation with a pinion 73. The quadrant is subjected to the influence of spring means (not shown) tending to urge the quadrant inwardly. A free-wheeling dog clutch 74 (operative in one direction of rotation only) is provided between the pinion 73 and the vertical cam shaft 29. The quadrant 72 is fulcrummed at 75 beneath the top plate 12 and, as shown in Figures 5 and 6, is furnished with a roller 76 arranged to be acted upon by a cam 77 on the rotary head wheel gear 78 of the machine. Now normally the roller 76 is held clear of the operative bevelled surfaces of the cam 77 by reason of the engagement of the latch 71 with the quadrant 72. To initiate rotation of the cam shaft 29 to the extent of one revolution, the ring 69 is angularly displaced at a time determined by the chain 30 as aforesaid with the result that the latch 71 is disengaged from the quadrant 72, thereby releasing the latter and permitting it to swing inwardly so that the roller 76 lands upon the peripheral surface 78a of the head wheel gear 78. This rotates the pinion 73 in its free-wheeling direction so that no rotation will be imparted to the cam shaft 29. The next time the cam 77 comes round, however, it will act on the roller 76 and push the toothed quadrant 72 outwardly to the extent that it is re-engaged by the latch 71 and once again locked in its normal inoperative position. But in consequence of the quadrant being pushed outwardly in this manner, the pinion 73 is rotated in the reverse direction suchwise as to rotate the cam shaft 29 through a revolution.

The movements necessary to effect a complete yarn change, during one revolution of the cam shaft 29, will now be described. It will first be assumed that three of the grippers are in their normal rest positions such as that shown in Figure 1, in which position the hooked rod 16 of each such gripper is fully retracted and the latter is holding an inactive yarn Y in a non-feeding position. The fourth and running yarn Y¹ (see Figure 1) is feeding to the needles whilst the gripper corresponding to this yarn is in a partially raised position with the operative end of its hooked rod 16 projecting to a small extent only from the tube 13 and the tail end of the said rod on a level with the lateral extension 47 of the arm 43a. To initiate a yarn change, the bell crank lever 43 is first swung forwardly with the result that the extension 47 acts on and pushes forward the rod 16 of the partially raised gripper: as a consequence, the hook 17 is fully projected from the tube 13 of this particular gripper in readiness to engage the running yarn Y¹. Next, the lever 34 is swung forward to lift the pivoted element 31 and thereby cause the upwardly moving transverse pin 32 to raise all four grippers G to the chain line position indicated in Figure 1. This movement lowers the teeth 22 clear of the selector discs 23, whereupon the latter are immediately racked round one step. The gripper thereby selected to position a yarn Y favourably for introduction to the needles is that gripper whose tooth 22 now opposes a gap in the corresponding selector disc 23. At this phase, the lever 34, and hence also the element 31 and its pin 32, is swung down into its lowest position indicated in full lines, with the result that the selected gripper is permitted to fall under the action of its spring S into the low

position shown in Figure 8. Owing to this falling movement of the selected gripper a length Y² of the inactive yarn Y, still trapped by the said gripper, is favourably disposed for engagement by the placer 26 which has meanwhile been projected outwardly from the dial 51 as depicted in Figure 8. As the selected gripper falls, however, the pin 50 on the tail end of its hooked rod 16 rises and enters the groove or channel in the portion 48 on the lever arm 43a, and the latter commences to move forward to effect partial projection of the gripper hook 17 from the gripper tube 13. After the projected placer 26 has engaged the length Y² of yarn and been retracted to draw the said yarn into the needles, the lever arm 43a swings further forward to an extent sufficient to effect further projection of the hook 17 from the tube 13 and so release the yarn in the manner depicted in Figure 9. The said hook is thereupon immediately drawn back into the tube. Simultaneously, or practically so, with the newly presented yarn being taken by the needles, the rod 16 of the previously empty gripper (the hook 17 of which is now fully projected) is drawn back, by contact of a further transverse pin 32¹ on the pivoted element 31 with the upstanding pin 18 on the rod (see Figure 2), so that the hook engages the then feeding yarn Y¹ (see Figure 10), and withdraws the same from knitting. As the last mentioned rod is withdrawn for this purpose it not only grips the relevant yarn but also cuts it at the side nearest to the needles. It is convenient here to explain that the transverse pin 32¹ is fixed in the upper end of the pivoted element 31, this pin, which is common to all of the grippers, being omitted from Figure 3 for the sake of clarity. A backward turning movement of the element 31 to press on the pin 18 of the relevant gripper rod 16 is, of course, effected by co-operation of the pin 40 with the cam surface 11a aforesaid. At the final phase of the complete revolution of the cam shaft 29, the hooked end of rod 16 of the selected gripper is again partly projected, and the said gripper is raised by the pin 32 towards its normal rest position, thereby completing the sequence of timed movements necessary to effect the change of yarn.

In the modified form of the invention illustrated in Figures 11 and 12, each gripper G consists, as shown more clearly in Figure 12, of a straight bar-like member 79 of channel section to the closed side of which is attached an upstanding lug or ear 80 having drilled therein a hole through which the common fulcrum pin extends. The upper portion of the said lug or ear 80 is so shaped as to provide thereon a suitably shaped nose 80a arranged in line with and to be acted upon by pegs 81 on a drum 82 mounted immediately above the grippers. The drum 82 is mounted for rotation in an intermittent manner about a horizontal axis, and the pegs 81 are suitably pre-arranged in a plurality of axially spaced circular series or rows—one to each gripper. The leading end of each gripper is shaped to provide a jaw 83 adapted for co-operation with a small relatively movable jaw 84 pivotally mounted within the open side of the channel-section gripper. The leading end of a blade spring 85 fitted within the gripper is arranged in contact with the opposed inner side of a tail 84a on the pivoted gripper jaw whereby the two jaws 83 and 84 are normally held closed as shown in Figure 12. For acting on and pressing in the tail 84a of the pivoted gripper jaw 84

suchwise as to effect separation of the two jaws and so open the gripper at appropriate times, there is provided a slide 86 (Figure 12) which is movable longitudinally within limits, along the gripper. The side 86a of the slide 86 faces the open side of the gripper and has formed therein an elongated slot 87 through which protrudes a pin 88 on the tail 84a of the pivoted gripping jaw. When the jaw-actuating slide 86 is moved rearwardly, the forward edge of the elongated slot 87 acts on the pin 88 in such a way as to turn the pivoted gripping jaw 84 against the spring action and away from the companion jaw 83 to open the gripper. Conversely, by pushing the slide 86 forwards along the gripper, the tail 84a of the pivoted gripping jaw 84 is released with the result that the said jaw turns inwards under the spring action to close the gripper.

To enable the jaw-actuating slide of any one of the grippers G to be drawn rearwardly to open the jaws 83 and 84, the slide 86 is provided at its rear end with an upstanding butt 89 arranged to be acted upon by a downwardly extending arm 90a of a fulcrummed two-armed lever 90 the other arm 90b of which is fitted with a pin or roller engaged in an appropriately profiled upper track 91 of a grooved cylinder cam 92. This cam is secured upon a vertical shaft 93 adapted to be turned, by any suitable means, through one complete revolution at each of suitably spaced intervals of time. For pushing the jaw-actuating slide 86 of any of grippers forwards to close the corresponding jaws, there is provided a fulcrummed bell-crank lever 94 disposed with one arm 94a extending upwards for direct contact with the rear end of the slide 86 and its other arm 94b extending outwards and furnished with a pin or roller engaged in a lower profiled track 95 of the same grooved cylinder cam 92.

Each of the grippers is influenced by a tension spring S¹ whereby, whenever permitted to do so, the gripper is so turned that its jaws 83 and 84 are swung downwards to their lowest position indicated in full lines in Figure 11, and the upstanding butt 89 on the corresponding jaw-actuating slide 86 is swung up into its highest position behind the downwardly extending arm 90a of the lever 90.

The peg drum 82 for selectively controlling the grippers is provided at one end with a peripherally notched disc or flange 96, the notches 96a in which are adapted to be engaged seriatim by a profiled rib 97a on a cylinder cam 97 secured upon the upper end of the vertical cam shaft 93. Thus each time this shaft is turned through a complete revolution the peg drum 82 will be racked round one step.

The yarn placer 98 in this example consists of a hooked or like pivoted member mounted to turn immediately beneath the location at which dial needles 6 are projected outwards. The spindle 99 of the placer 98 is provided with a crank arm 100 which is suitably articulated to a horizontally disposed fulcrummed lever 101 furnished at its tail end with a depending pin or roller 102 engaged in the track 103 of a grooved plate cam 104 which is secured upon the vertical cam shaft 93.

The construction and arrangement of the modified mechanism are such that whenever a peg 81 on the drum 82 comes into contact with the nose 80a on the upstanding lug 80 of any one of the grippers (assuming the operative end of the latter to be held at that time in its lowest position), the gripper will be swung upwards against the action of its spring S¹ first into and then a little

beyond a horizontal position. So long as a peg 81 contacts the nose 80a during successive racking of the drum 82, the gripper will be maintained with its jaws swung up into their highest position. 5 But assuming a peg in the appropriate series or row to be missing then at the crucial rack of the drum 82 the gripper will be released and move under the influence of its spring as a consequence of which the jaws are swung down into their lowest position. It is to be clearly understood that whenever any one gripper is swung downwards another gripper will be simultaneously swung upwards, and vice versa, to effect a substitution of one yarn for another. Thus, with a 10 yarn in its feeding position so that it is being taken and knitted by the cylinder and dial needles, the jaws 83 and 84 of the corresponding gripper will be open and in their lowest position below the plane of the dial needles. Assuming 15 now this yarn is to be withdrawn from knitting, the gripper is first turned by a peg 81 on the drum 82 into a horizontal position so that its jaws, still open, embrace without gripping the yarn. At this stage the jaws are closed, by a forward 20 movement of the jaw-actuating slide 86, with the result that the still feeding yarn is gripped and breaks. Further turning movement of the gripper in the same direction swings the closed jaws up higher to move the yarn into its non-feeding 25 position. Simultaneously with these movements another of the grippers, holding between its closed jaws yarn to be substituted for that withdrawn, is released so that its jaws swing down from their highest to their lowest position, thereby drawing a straight length Y³ (Figure 11) 30 of the yarn into a favourable position for introduction to the needles. With these jaws still closed the placer 98 is caused to swing inwardly suchwise as to engage the relevant yarn and 35 sweep it into the needles at which moment the 40 jaws are opened to release the said yarn—by a rearward sliding movement of the corresponding jaw-actuating slide 86.

The lower end of the vertical cam shaft 93 may 45 have secured thereon a star or like wheel 105 adapted, by engagement with any appropriate means such as pins 106 on the hand wheel gear 107, to be turned through a complete revolution at a time.

50 An advantage of the improved mechanism is that the positions of the grippers are not required to be critical, so that no very precise adjustments either of the grippers or of the means for controlling the same are necessary. Also, there are 55 no tensioning means other than those normally provided between the yarn supplies and the needles.

60 By reason of the fact that in both of the examples described the various cams are mounted upon a common cam shaft, the cams may be made individually adjustable angularly about the shaft suchwise as to enable the moving parts of the striping attachment to be accurately timed with respect to each other.

65 What I claim is:

1. In a knitting machine, in combination, at least one set of needles, a fixed guide through which a yarn from a supply passes when feeding to said needles, a yarn gripper, means for moving said gripper from one position in which it grips said yarn and holds it in a non-feeding position clear of the needles to another position in which the yarn, still held by the gripper, is favourably disposed for introduction to the

needles, and placer means operable to engage the yarn so disposed and to take it to the needles.

2. In a knitting machine, in combination, at least one set of needles, a fixed guide through which a yarn from a supply passes when feeding to said needles, a yarn gripper furnished with relatively movable gripping parts, means for moving said gripper from one position in which it grips said yarn and holds it in a non-feeding position clear of the needles to another position in which the yarn, still held by the gripper, is favourably disposed for introduction to the needles, placer means operable to engage the yarn so disposed and to take it to the needles, and means operable to effect relative movement of the aforementioned gripping parts suchwise as to release a held yarn following introduction thereof to the needles by the placer means.

3. A combination according to claim 2, wherein to withdraw the said yarn from knitting the gripper is movable and the relatively movable gripping parts are operable to engage and trap the yarn and hold it in its non-feeding position.

4. A combination according to claim 3, wherein severance of the withdrawn yarn is effected by a shearing action resulting from relative movement between the gripping parts.

5. In a knitting machine, in combination, at least one set of needles, a series of fixed guides through each of which a yarn from a supply passes when feeding to said needles, a corresponding series of yarn grippers furnished with relatively movable gripping parts and operable selectively for effecting substitution of one yarn for another, means for moving a selected gripper from one position in which it grips the relevant yarn and holds it in a non-feeding position clear of the needles to another position in which the said yarn, still held by the gripper, is favourably disposed for introduction to the needles, placer means operable to engage a yarn so disposed and to take it to the needles, and means operable to effect relative movement of the gripping parts of a selected gripper suchwise as to release a held yarn following introduction thereof to the needles by the placer means, the eventual withdrawal of this yarn from knitting being effectible by reverse movement of the aforementioned selected gripper and operation of the relatively movable gripper parts to engage and trap the yarn and again hold it in its non-feeding position.

6. A combination according to claim 5, which includes a single yarn placing member common to all of the grippers.

7. A combination according to claim 5, which includes cam-operated means, operable in timed relation with the movements of the grippers, for effecting and controlling the relative movements of the gripping parts at the operative ends of such grippers.

8. In a knitting machine, in combination, at least one set of needles, a series of fixed guides through each of which a yarn from a supply passes when feeding to said needles, a corresponding series of yarn grippers operable selectively for effecting substitution of one yarn for another, each of said grippers consisting of a pivoted tubular member provided with springy portions at its operative end, and, contained within the said member, a longitudinally slidabile rod having a hook which is projectible beyond and retractable into the operative end of the tubular member, means for moving a selected gripper, from one position in which it grips the

relevant yarn and holds it in a non-feeding position clear of the needles to another position in which the said yarn, still held by the gripper, is favourably disposed for introduction to the needles, placer means operable to engage a yarn so disposed and to take it to the needles, and means operable to effect projection of the hooked rod of a selected gripper suchwise as to release a held yarn following introduction thereof to the needles by the placer means, the eventual withdrawal of this yarn from knitting being effectible by reverse movement of the selected gripper and retraction of its hooked rod to engage and trap the yarn and again hold it in its non-feeding position.

9. In a knitting machine, in combination, at least one set of needles, a series of fixed guides through each of which a yarn from a supply passes when feeding to said needles, a corresponding series of yarn grippers furnished with relatively movable gripping parts and operable selectively for effecting substitution of one yarn for another, a revolute assemblage of selector discs, one to each yarn gripper, said discs having thereon pre-arranged formations, controlled means for turning the said assemblage a step at a time, the arrangement being such that a gripper selected by the relevant selector disc is permitted to move from one position in which it grips the relevant yarn and holds it in a non-feeding position clear of the needles to another position in which the said yarn, still held by the gripper, is favourably disposed for introduction to the needles, placer means operable to engage a yarn so disposed and to take it to the needles, and means operable to effect relative movement of the gripping parts of a selected gripper suchwise as to release a held yarn following introduction thereof to the needles by the placer means, the eventual withdrawal of this yarn from knitting being effectible by reverse movement of the aforementioned selected gripper imparted by a formation on the relevant selector disc and operation of the relatively movable gripper parts to engage and trap the yarn and again hold it in its non-feeding position.

10. A combination according to claim 9, wherein in each of the grippers is influenced by spring means by which movement of the gripper in the appropriate direction is effected, when permitted by the corresponding selector disc.

11. In a knitting machine, in combination, a rotary cylinder, needles in said cylinder, a tricked dial rotatable together with the cylinder, dial needles in tricks of said dial, a dial cam plate fitted with cams for actuating the dial needles, a series of fixed guides through each of which a yarn from a supply passes when feeding to the cylinder and dial needles, a corresponding series of yarn grippers furnished with relatively movable gripping parts and operable selectively for effecting substitution of one yarn for another, means for moving a selected gripper from one position in which it grips the relevant yarn and holds it in a non-feeding position clear of the needles to another position in which the said yarn, still held by the gripper, is favourably disposed for introduction to the needles, a yarn placer for engaging a yarn so disposed and taking it to the cylinder and dial needles, said placer having a shank with a hooked extremity and being located in one of the needle tricks in the dial, means associated with the dial cam plate for projecting the placer from and retracting it into the dial for the purposes specified, and means

operable to effect relative movement of the gripping parts of a selected gripper suchwise as to release a held yarn following introduction thereof to the needles by the placer, the eventual withdrawal of this yarn from knitting being effectible by reverse movement of the aforementioned selected gripper and operation of the relatively movable gripper parts to engage and trap the yarn and again hold it in its non-feeding position.

12. In a knitting machine, in combination, at least one set of needles, a series of fixed guides through each of which a yarn from a supply passes when feeding to said needles, a corresponding series of yarn grippers furnished with relatively movable gripping parts, selector means for determining selective actuation of the grippers to effect substitution of one yarn for another at required times, a rotary cam shaft, means for turning the said shaft to a pre-determined extent at each of desired intervals of time, timing means for dictating the intervals at which the shaft is turned, means controlled from a cam on the cam shaft for operating the selector means, the arrangement being such that a selected gripper is permitted to move from one position in which it grips the relevant yarn and holds it in a non-feeding position clear of the needles to another position in which the said yarn, still held by the gripper, is favourably disposed for introduction to the needles, placer means operable to engage a yarn so disposed and to take it to the needles, and means operable from another cam on the aforesaid cam shaft to effect relative movement of the gripping parts of a selected gripper suchwise as to release a held yarn following introduction thereof to the needles by the placer means, the eventual withdrawal of this yarn from knitting being effectible by reverse movement of the aforementioned selected gripper and operation of the relatively movable gripper parts to engage and trap the yarn and again hold it in its non-feeding position.

13. A combination according to claim 12, wherein an assemblage of selector discs with pre-arranged formations thereon is provided for selecting the grippers, this assemblage being associated and rotatable together with a toothed wheel the notches in which are engageable seriatim by a profiled rib on a cylinder cam on the cam shaft.

14. In a knitting machine, in combination, at least one set of needles, a series of fixed guides through each of which a yarn from a supply passes when feeding to said needles, a corresponding series of yarn grippers operable selectively for effecting substitution of one yarn for another, each of said grippers consisting of a pivoted tubular member provided with springy portions at its operative end, and, contained within the said member, a longitudinally slidable rod having a hook which is projectible beyond and retractible into the operative end of the tubular member, selector means for determining selective actuation of the grippers, a rotary cam shaft, means for turning the said shaft to a pre-determined extent at each of desired intervals of time, timing means for dictating the intervals at which the said shaft is turned, means controlled from a cam on the cam shaft for operating the selector means, the arrangement being such that a selected gripper is permitted to move from one position in which it grips the relevant yarn and holds it in a non-feeding position clear of the needles to another

position in which the said yarn, still held by the gripper, is favourably disposed for introduction to the needles, placer means operable to engage a yarn so disposed and to take it to the needles, pins 5 on the aforesaid longitudinal slidable rods, levers having associated therewith parts for action upon said pins, grooved cylinder cams on the rotary cam shaft, said cams having therein tracks in which are engaged other parts on said levers, one 10 of said grooved cylinder cams causing projection of the rod from the pivoted tubular member of a selected gripper to release a held yarn following introduction thereof to the needles by the placer means, the eventual withdrawal of this 15 yarn from knitting being effectible by reverse movement of the selected gripper caused by appropriate operation of the selector means and retraction of the slidable rod by the appropriate grooved cylinder cam to engage and trap the yarn and again hold it in its non-feeding position.

15. A combination according to claim 14, wherein a member movably mounted on one of the levers is provided with an element which extends transversely beneath the tubular members of the 20 grippers and functions both to control downward swinging movement of any selected gripper (to dispose a yarn favourably for introduction to the needles) and also to raise the gripper to a position in which it can engage the said yarn when 25 this is required to be withdrawn from knitting, the said movable member being subject to cam control and provided with a second element arranged for action upon pins on the gripper rods, for the purpose specified.

16. In a knitting machine, in combination, a rotary cylinder, needles in said cylinder, a tricked dial rotatable together with the cylinder, dial needles in the tricks of said dial, a dial cam plate fitted with cams for actuating the dial needles, 30 a series of fixed guides through each of which a yarn from a supply passes when feeding to the cylinder and dial needles, a corresponding series of yarn grippers furnished with relatively movable gripping parts and operable selectively for effecting substitution of one yarn for another, means for moving a selected gripper from one 35 position in which it grips the relevant yarn and holds it in a non-feeding position clear of the needles to another position in which the said yarn, still held by the gripper, is favourably disposed for introduction to the needles, a yarn placer for engaging a yarn so disposed and taking it to the cylinder and dial needles, said placer having a shank provided with a butt and also with a hooked 40 extremity and being located in one of the needle tricks in the dial, a forked lever which has a cam thereon and is engaged with said butt, a component which is rotatable with the dial and has the forked lever pivotally mounted thereon, pins 45 associated with the dial cam plate for co-operation with the cam on the forked lever for the purpose of projecting the placer from and retracting it into the dial, and means operable to effect relative movement of the gripping parts of a selected gripper suchwise as to release a held yarn following introduction thereof to the needles by the placer, the eventual withdrawal of this yarn from knitting being effectible by reverse movement of the aforementioned selected gripper and 50 operation of the relatively movable gripper parts to engage and trap the yarn and again hold it in its non-feeding position.

17. In a knitting machine, in combination, at least one set of needles, a series of fixed guides through each of which a yarn from a supply 55

passes when feeding to said needles, a corresponding series of yarn grippers furnished with relatively movable gripping parts, selector means for determining selective actuation of the grippers to effect substitution of one yarn for another at required times, a rotary cam shaft, a pinion, a free-wheeling clutch by which the rotary cam shaft is coupled to said pinion, a toothed quadrant with which the pinion is arranged in mesh, a cam on a rotary component of the machine for actuating the toothed quadrant and so turning the cam shaft, a latch device normally engaged with the toothed quadrant to hold the latter clear of the last mentioned cam, a timing member, connections between the said timing member and the latch device which connections are operable to release the quadrant for actuation by the said cam at the dictates of the timing member, means controlled from a cam on the cam shaft for operating the selector means, the arrangement being such that a selected gripper is permitted to move from one position in which it grips the relevant yarn and holds it in a non-feeding position clear of the needles to another position in which the said
